POCKET RING-SIZE GAUGE

Lyman W. Bloomberg, 1804 5th St., Clay Center, Kans.

Filed Dec. 12, 1961, Ser. No. 67,874

Term of patent 14 years

(Cl. D52—6)

FIG. 1 is a top plan view of the pocket ring-size gauge in an open condition showing my new design;

FIG. 2 is a bottom plan view thereof in an open condition;

FIG. 3 is a top plan view thereof in a closed condition;

FIG. 4 is a bottom plan view thereof in a closed condition; and

FIG. 5 is an edge elevational view of the pocket ring-size gauge.

I claim:

The ornamental design for a pocket ring-size gauge, as shown.
